(74) Attorney, Agent, or Firm — Perkins Coie LLP

(57) **CLAIM**

The ornamental design for a packaging, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of a first embodiment of a packaging showing our new design;

FIG. 2 is a rear perspective view thereof;

FIG. 3 is a front elevational view thereof;

FIG. 4 is a rear elevational view thereof;

FIG. 5 is a front perspective view of a second embodiment of a packaging;

FIG. 6 is a rear perspective view thereof;

FIG. 7 is a front elevational view thereof; and,

FIG. 8 is a rear elevational view thereof.

**1 Claim, 4 Drawing Sheets
(2 of 4 Drawing Sheet(s) Filed in Color)**
